HANDBAG

Clarence Brinkerhoff, Denver, Colo.

Application January 21, 1936, Serial No. 60,043

3 Claims. (Cl. 150—35)

This invention relates to a lady's handbag or case. Usually a woman carries her money in her handbag where it becomes mingled with cosmetics, handkerchiefs, etc. It is rather annoying for a woman to make change before a cashier, streetcar conductor, etc., since it usually requires removal of the major portion of the contents of the bag in order to reach a piece of small change.

The principal object of this invention is to provide a construction for handbags or hand-cases in which coins will be instantly and easily available regardless of the remaining contents of the bag.

Another object is to provide a coin carrying means in combination with a handbag which will maintain the various coins separated, and visible in order that the desired coin may be quickly and easily found, and, so that when not in use, the coins will be securely enclosed by an inconspicuous enclosure.

Other objects and advantages reside in the detail construction of the invention, which is designed for simplicity, economy, and efficiency. These will become more apparent from the following description.

In the following detailed description of the invention reference is had to the accompanying drawings which form a part thereof. Like numerals refer to like parts in all views of the drawings and throughout the description.

In the drawings:—

Fig. 1 is a perspective view of a woman's handbag or carrying case with the invention applied thereto. In this view, the coin carrier is illustrated partially open and the bag is illustrated closed.

Fig. 2 is a similar view illustrating the coin carrier closed and the bag open.

Fig. 3 is a longitudinal section through the coin carrying portion illustrating it in the open position.

Fig. 4 is a cross section therethrough, taken on the line 4—4, Fig. 2.

The invention comprises a case 10 which may have any suitable configuration or design and any desired surface ornamentation. The case 10 is provided with a hinged side 11 which may be held closed by any suitable catch or fastener.

The side 11 is preferably provided with folding pockets 13. The case 10 is preferably provided with end pockets 14 and with any suitable carrying handle or strap 15.

The coin carrying portion of this device consists of a series of coin compartments 16, provided with a false bottom 17, and positioned over

the entire top of the bag 10. The coin compartments 16 are provided with a flexible cover 18. The cover 18, slides in side channel members 19 which extend along both sides of the top of the coin compartments 16, thence curve downwardly around one end thereof as indicated at 20, to return beneath the bottom 17 and above a false top 21 over the bag.

The flexible cover 18 may be constructed in any desired manner. As illustrated, it consists of a 10 series of cross slats 22 secured together by a flexible covering of leather, fabric or similar material. The extremities of the slats project into the guide channels 19 and slide therein. This cover however, could be formed of a single 15 piece of flexible metal or the like.

The extremity of the flexible top 18 is provided with a catch post 23 which serves both as a finger hold for opening and closing the top 18 and also as a catch to corporate with a suitable 20 snap 24 for locking the top in the closed portion.

It is preferred to form the compartments 16 of different sizes to accommodate coins of various sizes, and it is preferred to have the smaller compartments for the smaller coins at the extremity which is first opened upon movement of the cover 18.

In use the device may be conveniently held under the left arm and grasped with the left hand. The right hand then can be used to unfasten the snap 24 and slide the top 18 open the desired amount. This exposes the coins or tokens in the compartment 16 so that they are easily visible and easily reached. Paper money can be kept in toe pockets 13, if desired. Transfers, receipts, etc. may be conveniently kept in the pockets 16 where they can be easily reached without opening the side 11.

While the invention has been illustrated with the flexible lid 18 longitudinally movable, it is conceivable that this might, on bags of certain design, be laterally movable.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A case of the character described comprising: closed end walls; one closed side wall; a bottom extending between said closed end walls; an open top; a false top positioned below said open top; a hinged side positioned below said false top 50 55

- 5 opposite said closed side wall; a false bottom spaced above said false top; a longitudinally extending, flexible cover for closing the entire length of said open top; and means for guiding said cover downwardly inside one end wall to a position between said false top and said false bottom when it is moved to the open position.
2. A case of the character described comprising: closed end walls; one closed side wall; a bottom extending between said closed end walls; an open top; a false top positioned below said open top; a hinged side positioned below said false top opposite said closed side wall; folding pockets mounted between said hinged side and said closed side wall; a false bottom spaced above said false top; a longitudinally extending, flexible cover for closing the entire length of said open top; and means for guiding said cover downwardly inside one end wall to a position between said false top and said false bottom when it is moved to the open position, said folding pockets acting to move the contents outward from beneath said false top when said hinged side is opened.
- 10
- 15
- 20

3. A case of the character described comprising: closed end walls; one closed side wall; a bottom extending between said closed end walls; an open top; a false top positioned below said open top; a hinged side positioned below said false top opposite said closed side wall; a false bottom spaced above said false top; a longitudinally extending, flexible cover for closing the entire length of said open top; means for guiding said cover downwardly inside one end wall to a position between said false top and said false bottom when it is moved to the open position; a series of partitions extending laterally between the side walls above said false bottom so as to form a longitudinally extending series of compartments 15 across said open top so that said compartments will be successively opened and closed as said cover is moved to or from its position between said false bottom and said false top.

CLARENCE BRINKERHOFF.
